UNITED STATES PATENT OFFICE

2,380,227

MEANS FOR SLASHING PLATFORMS
AND INSOLESLouis G. Freeman, Jr., Cincinnati, Ohio, assignor
to Benjamin W. Freeman, Cincinnati, Ohio

Application January 24, 1944, Serial No. 519,510

12 Claims.

(Cl. 12—40)

For many years it has been the custom in order to render insoles more flexible to slash the insole part of the way through by means of a die or dies.

With the advent of the platform shoe it became increasingly necessary to slash these platforms because of the rigidity of the material used in the manufacture of the platform.

In slashing these platforms with an ordinary die the slashes were perpendicular to the plane of the platform and if the slashes were long enough to extend to the edges of the platform it was found that when the cover was applied over the platform and the ensuing stitching or cementing under pressure operations were completed that the portions at the edge of the platform adjacent the slashes extended outward causing bulges along the edge of the platform where it was slashed.

If the platform covers were either stitched or cemented on, it was found that when the shoes were worn the continued flexing of the platform at the slashed points tended to break or crack.

In slashing the platform the slashing knives penetrated approximately $\frac{2}{3}$ or more through the platform material, resulting in $\frac{1}{3}$ or less of the platform material unslashed. This small amount of material is all that is left to hold the front part of the platform to the rear part and continued flexing eventually cracks or breaks at the slashed points.

In order to provide more strength to the platform, a die was used which did not cut across the entire width of the platform, leaving a margin between the end of the slash and the edge of the platform. This method left an unslashed portion for the platform cover to be cemented or stitched to but it also greatly reduced the amount of flexibility in the platform and tended to defeat the purpose of the slashing; although it did prevent the bulging at the edge of the platform adjacent the slashes.

Inasmuch as the platforms grade regularly like insoles or outsoles as to size and width, there was a great variation in the space between the end of the slash and the edge of the platform unless a series of slashing dies were used.

Another objection to this method is that platforms must be placed more or less accurately in the slashing die so that the slashes would be spaced uniformly from both edges.

With the slashes at an angle instead of vertical, there would be no tendency of the edges of the platform to bulge out when pressure was exerted against the platform either when applying pressure in cementing the cover to the platform,

in stitching the cover to the platform, or the weight of the body when walking; the theory being that there will be platform material under the slash to support this slash.

5 When a platform cover is stitched on to the platform the needle with slanted slashes penetrates through the slashed portions anchoring them together and prevents the platform from breaking at the slashing points when the slashes 10 cover the entire width of the platform as in the old straight up and down method of slashing.

It is the object of the present invention to provide a mechanism and practice for readily forming these desirable slanting slashes. Essentially I provide a movable die carriage with a die thereon which during its forward motion will travel across the surface of the platform which is clamped tightly on the gauge plate and the angularly set knives of the die will slash the platform across its entire width.

One problem in such an operation is that the knives tend to tear rather than cut the platform material, and I provide a knife so shaped and so sharpened that I eliminate this tearing.

25 Another problem which has been solved is to prevent the knife from contacting the insole on the return trip of the die carriage and means is used to raise the knives before the return of the die carriage to its rearward position.

30 To the attainment of the foregoing and other objects that will appear as the description proceeds, reference may be made to the accompanying drawings in which like numerals designate like parts and in which such parts of the machine as have been necessary to show the operation of the die have been illustrated.

Reference is now made to the drawings in which:

Figure 1 is a perspective taken from the front 46 of the machine equipped according to my invention.

Figure 2 is a side elevation of the press equipment according to my invention, shown as a section through the frame and carriage.

45 Figure 3 is a perspective of the work holder.

Figure 4 is a side elevation of the die in position with the wedge removed.

Figure 5 is a view like that of Figure 4, with the wedge inserted.

50 Figure 6 is a plan view of the entire die structure, taken from beneath the device.

The die carriage A carries the upper die unit B in operative relation to the work support C, which in turn carries the gauge plate and the masking or clamping means D.

The die unit B consists of a base plate 1 by means of which the unit is secured to the die carriage A in any desired manner.

Resiliently mounted on the plate 1, by means of posts 4 (four being used in this instance), and springs 5, washers 6 and screws 7, is the wedge receiving plate 8 to which is rigidly mounted the cutter blade block 9. The springs preferably carry a bushing 5a which engages the washers and bottom against the plate 8 when the springs are compressed. The cutting blades 10 fit in suitable slots in the block and are clamped rigidly and positioned there by means of clamp bar 12 and screws 13. A bevel 15 is provided on the wedge receiving plate 8 on the side nearest the base plate 1 and on the edge facing the wedge bar 16.

Rigidly secured to the base plate 1 are recessed gibs 17 perpendicular or at right angles to the beveled portion of the wedge receiving plate 8.

The wedge 14 is formed at one end of a bar 16, which is provided with lips 18 to cooperate with the recessed gibs 17 so as to allow the wedge bar 16 to slide freely in a horizontal position but to prevent any movement of the wedge bar 16 from a vertical or up and down movement.

When the wedge 16 moves forward the tapered or wedged edge of the wedge engages the corresponding bevel 15 of the wedge receiving plate 8 and as the wedge 16 proceeds forward it separates the plate 8 from the base plate 1 against the action of the springs 5 and when the wedge 16 arrives at its foremost position the flat surface of the plate 8 is resting on the flat surface of the wedge bar 16, so that the wedge receiving plate and the cutter blade block 9 are parallel with the base plate 1 and the cutting knives 10 are in cutting position.

Rigidly secured at the rearward end of the wedge bar 16 is a contact block 19 which serves to move the wedge 16 into and out of position as the carriage moves inwardly and, as it passes the work after completing the cutting operation at the end of the forward stroke.

The masking or clamping unit D is comprised of a gauge plate 30 provided with perforations 31 which are so located as to cooperate with pins 32 located on the work support C and are the means for properly locating the unit D on to the work support C in relation to the die unit B.

Rigid bars 33 are rigidly attached to the gauge plate 30 to cooperate with the clamping means 34 pivotally and resiliently attached to the work support.

Clamping plate 35 is rigidly attached to the gauge plate 30 but elevated to a predetermined height therefrom by means of studs 36, a sufficient number of which are used to provide adequate support to the clamping plate.

The upper surface of the clamping plate 35 has been knurled or roughened to prevent the work from moving during the cutting operation.

A clamping mask 37 provided with aligning plates 38 is pivotally mounted to the clamping plate 35 by means of hinges 39.

The clamping mask 37 extends forward so as to provide leverage for the operator in holding the work securely in position. The forward part of the clamping mask can be used as a handle as at 40.

Rigidly secured to the gauge plate 30 is a wedge retracting block 41. A wedge inserting block 50 is rigidly attached to a bracket on the machine which carries the die carriage actuating mechanism.

The operation of the die is as follows:

The die unit B with the block 19 at its rearmost position is placed in the die carriage A and locked therein while the die carriage is at its foremost position. By means of operating mechanism fully described in Freeman Patent No. 2,084,335, the die carriage together with the die unit B is returned to its rearmost position. As the die carriage approaches its rearmost position the contact block 19 contacts the wedge inserting block 50, stopping the block 19 and the wedge 16. As the die carriage proceeds with the die unit B securely locked thereto it continues to move rearwardly. The wedge 16 at the tapered end 19 contacts the beveled edge 15 of the plate 8 and enters between the plate 8 and the base plate 1, lowering the cutter blades 10 to their normal working position by the time the die carriage and die unit B reach its rearmost or rest position. This relation of parts is shown in Fig. 2.

The masking or clamping means unit D is then located on to the work support by means of the perforations 31 and the locating pins 32 are held in position by the pivoting clamps 34. The handle portion of the mask clamp is then raised as at 40 and the work placed on the roughened portion of the clamping plate 35 with the side of the work to be operated upon uppermost. The mask clamp is then lowered and the work aligned to its proper position and then the operator depresses the mask clamp at 40, thus holding the work rigidly in proper operating position.

Upon treading the machine the die carriage together with the die unit B starts its forward motion and as the cutting blades 10 pass through the work-piece they cause slashes to be made.

By setting the knives at various angles the angles of the slashes in the work-piece can be varied.

After the cutting blades 10 have passed through the work-piece and beyond the forward edge of the clamping plate 35 the contact block 19 contacts the wedge retracting block 41, stopping the motion of the wedge. The die carriage and the die unit B rigidly locked therein continues to move forwardly and the wedge 16 is thereby retracted from the space between the plate 8 and the base plate 1. The action of the springs 5 force the plate 8 against the plate 1, thus raising or reducing the height of the die.

If the machine is so connected up as to operate as a cut-out machine, as shown in the Freeman patent above referred to, it is apparent that the work support C may rise and retract as it would do in forming cut-outs or print marking, and the mechanism now described would not interfere with this movement.

Upon completion of the cycle of the work support the die carriage moves to its rearward or rest position and the die unit B, because of the retracted position of the wedge clears the work which is still clamped in the unit D.

As the die carriage continues its rearward movement, the block 19 contacts the block 50 and re-enters the wedge 16 between the plate 8 and the base plate 1, lowering the cutters again to their normal height, whereupon another piece of work E may be mounted, and the operation repeated.

In connection with the structure of the knives, it will be noted that they are separate thin blades set into the holder, and that each one is in the form roughly of a rounded triangle with the advance edge in the cutting direction sharpened in

a fairly wide taper extending across the round tip or apex.

This is not a limitation on the invention as no doubt other forms of slicing knives or slashing knives would serve.

Whereas it is a great advantage to provide for a slashing die which can be very simply placed in the standard machine of Freeman construction, still the invention herein embodies more than this particular adaptation. Thus if the sliding wedge construction were placed on a sliding holder and operated upon the gauge plate thereof in the same manner that in the present instance the wedge device acts on the knife holder, it is apparent that the knives could be held in fixed position and the work holder moved to cause the slashing. The wedge bar block 49, might then be extended in the opposite direction to the one illustrated so that the wedge would be inserted beneath the plate when the same was in its forward position and pulled away from wedging position after the work has been passed under the slashing knives.

In its essence, my invention consists in moving a piece of work or slashing knives with reference to each other so that the knives traverse the work in a plane parallel to its surface, the to and fro motion being employed to elevate the support either for the work or the slashing knives when the parts are in one position, and lower it when the parts are in another, permitting a passing stroke of the instrumentalities in the return operation, the instrumentalities being so spaced that the knives do not contact the work. With such a construction applied to slantwise slashing, the principal objectives of my invention are performed. Then from the other point of view, I have provided for an arrangement in a standard cut-out press for use in decorating shoe parts for a slashing knife mounting which takes advantage of the traversing movement of the die holder to slash the work.

Having thus described my invention, what I claim as new and desire to secure by Letters Patent is:

1. In a machine for forming slashes in pieces of work for shoes and the like, a cutting die comprising a support and a series of separate blades mounted therein at the desired angle, means for moving said support in the plane of the work, and means for supporting the work in gauged position, and means for increasing the spacing of the die support and the work support during the return motion of the die support after a stroke during which the blades pass through the work.

2. In a machine for forming slashes in pieces of work for shoes and the like, a cutting die comprising a slashing blade set at the desired angle, means for moving said support in the plane of the work, and means for supporting the work in gauged position, and means for increasing the spacing of the die support and the work support during the return motion of the die support after a stroke during which the slashing blade passes through the work.

3. In a machine for forming slashes in pieces of work for shoes and the like, a cutting die comprising a slashing blade set at the desired angle, means for supporting the work in a gauged position, a support for the die, means for sliding the supporting means and support relative to each other in the same plane so that the slashing blade passes through the work in the plane of the

work, and means operative during a portion of said movement to space the said supports toward each other during the slashing stroke, and space them further from each other during the return stroke.

4. In a machine for forming slashes in pieces of work for shoes and the like, a cutting die comprising a slashing blade set at the desired angle, a support for the die, means for supporting the work, means for moving the die support in the plane of the work support where during a movement of the same the blade slashes the work and means for spacing the die support so that the blade will not reach the work during the return portion of the movement of the die support, comprising means for resiliently mounting the said support, a wedge member movable to force itself beneath the support and raise it, and abutments to engage the wedge member to move it beneath the support during the slashing stroke of the support and remove it from beneath the support during the return stroke thereof.

5. In a machine for forming slashes in pieces of work for shoes and the like, a cutting die comprising a slashing blade set at the desired angle, a support for the die, means for supporting the work, means for moving the die support in the plane of the work support where during a movement of the same the blade slashes the work and means for spacing the die support so that the blade will not reach the work during the return portion of the movement of the die support, comprising means for resiliently mounting the said support, a wedge member movable to force itself beneath the support and raise it, and abutments to engage the wedge member to move it beneath the support during the slashing stroke of the support and remove it from beneath the support during the return stroke thereof, the said means comprising an abutment which engages wedge opposing its movement along with the die support in one direction, and an abutment opposing its movement along with the support, in the other direction, said wedge remaining in the position enforced by one abutment until the other abutment engages it.

6. In a machine for forming slashes in pieces of work for shoes and the like, a cutting die comprising a slashing blade set at the desired angle, a support for the die, means for supporting the work, means for moving the die support in the plane of the work support where during a movement of the same the blade slashes the work and means for spacing the die support so that the blade will not reach the work during the return portion of the movement of the die support, comprising means for resiliently mounting the said support, a wedge member movable to force itself beneath the support and raise it, and abutments to engage the wedge member to move it beneath the support during the slashing stroke of the support and remove it from beneath the support during the return stroke thereof, the said means comprising an abutment which engages wedge opposing its movement along with the die support in one direction, and an abutment opposing its movement along with the support, in the other direction, said wedge remaining in the position enforced by one abutment until the other abutment engages it, the first noted abutment located so as to drive the wedge under the die support when the support moves away from above the work on the work support on its return stroke from slashing the work, and the second noted abutment placed so as to pull the wedge from

under the die support, when the support has passed beyond the work support in its slashing stroke.

7. In combination with a cut-out machine having a work support and a die carriage movable from an idle position away from above the work support, to a position over the work support, an attachment for converting the said machine for slashing shoe parts and the like comprising a work holder for locating the work on the work support, and a slashing die holder for locating a slashing blade on the carriage, and means effective upon the motion of the carriage to move the die support into and out of work contacting position.

8. In combination with a cut-out machine having a work support and a die carriage movable from an idle position away from above the work support, to a position over the work support, an attachment for converting the said machine for slashing shoe parts and the like comprising a work holder for locating the work on the work support, and a slashing die holder for locating a slashing blade on the carriage, and means effective upon the motion of the carriage to move the die support into and out of work contacting position, said means comprising resilient means for mounting the die on the die support, a wedge mounted slidably on the die support, and means for engaging said wedge to move it so as to elevate the die or permit the die to resume its resiliently held position.

9. In combination with a cut-out machine having a work support and a die carriage movable from an idle position away from above the work support, to a position over the work support, an attachment for converting the said machine for

slashing shoe parts and the like comprising a work holder for locating the work on the work support, and a slashing die holder for locating a slashing blade on the carriage, and means effective upon the motion of the carriage to move the die support into and out of work contacting position, said means comprising resilient means for mounting the die on the die support, a wedge mounted slidably on the die support, and means for engaging said wedge to move it so as to elevate the die or permit the die to resume its resiliently held position, said means comprising an abutment carried by the wedge, an abutment on the machine to engage the abutment in opposition to the movement of the carriage in its stroke away from the work support, and an abutment located on the work holder to engage the wedge abutment after the carriage has moved the blade past the work.

10. The machine of claim 1 in which the blades are shaped as round triangles sharpened on the edges advanced toward the work in slashing, as well as on the rounded apices of the triangles.

11. The machine of claim 2 in which the blade is in the form of a rounded triangle sharpened on the edge advanced toward the work in slashing, as well as on the round apex of the triangle.

12. A slashing die attachment for the reciprocating carriage of a cut-out machine, comprising a mounting plate, mounted on the carriage, a slide on the said plate having a wedge element at one end thereof, a die supporting plate mounted on spring posts on the mounting plate over the wedge path, said slide having a projection thereon serving as an abutment, the said die comprising a slashing blade.

LOUIS G. FREEMAN, JR.
